UNITED STATES PATENT OFFICE.

JEAN BABATÉ, OF PARIS, FRANCE, ASSIGNEE TO SOCIÉTÉ LE MATIN, OF PARIS, FRANCE, A FRENCH COMPANY.

HEARTH FOR TYPE FOUNDRY AND THE LIKE.

Application filed June 13, 1927, Serial No. 198,609, and in France June 25, 1926.

My invention relates to type founding hearths and the like, especially to those adapted for the moulding of stereotype plates for rotary printing machines and particularly for newspaper printing machines which require the use of a comparatively great amount of metal in a comparatively short time.

According to my invention the furnace 10 flames and gases after heating in a uniform manner the whole surface of the crucible pass over the metal bath under a vault and then into an exhaust pipe. Thus the bath is not exposed to an excessive cooling and the oil, 15 rosin and fat brought into the bath are burnt at about 500° C., their combustion having for further advantage the reduction of the slag. The vault is preferably heat insulated.

In a preferred form of execution the space 20 between the crucible and the refractory lining of the hearth is divided into several flues so as to obtain as long a distance as possible for the travel of the gases. For instance the gases may be caused to travel 25 through two successive superposed flues. The heating is improved by this feature and by suitable regulating means to be disclosed hereinafter and the consequent lesser consumption of fuel allows a speedier melting 30 of the metal than heretofore and the bath need not in some cases be stirred at all. The vault only covers part of the bath, the remainder being covered by a flat cover through which pass the metal suction pipe 35 and the stirring instruments when necessary. The two corresponding parts of the bath itself are separated by a metal gauze disposed throughout its depth in view of separating the part where the combustion of the impurities takes place and that wherefrom the metal is taken out.

A device is besides used for introducing the metal and old plates to be melted without allowing fresh air to enter with it, which 45 would cool the bath.

My improved hearth keeps its heat for a long time provided the exhaust pipe is closed. As oil burners have a greater efficiency at full load, it is preferable to use 50 them fully open and to interrupt them, when necessary, the exhaust being simultaneously closed.

On appended drawings I have shown by way of example two forms of execution of 55 my invention.

Figs. 1, 2 and 3 are a vertical longitudinal section a vertical transversal section and a plan view of a first form of execution.

Figs. 4, 5 and 6 are similar views of a second form of execution.

The crucible 15 is borne by a heat insulated metal frame 16 lined with a refractory material. In the middle of the vertical distance separating the edges of the crucible and the bottom of the frame are disposed two horizontal partitions 17, 18 so as to form a lower flue 19 extending under the whole length of the crucible and two upper flues 20, 21 extending on each side of the crucible. A burner 22 is disposed at the entrance of 70 the lower crucible. The flames follow the path shown in dotted lines on Fig. 4. They pass through the lower flue and in the opposite direction through the top flues. The crucible 15 is closed by the vault 23 over a little more than half its length and by the flat cover 24 over the remainder. The vault 23 is provided with two pipes 25, 26 the ends of which pass through the walls of the end of the hearth and open in the top flues 20, 21. This vault is also provided with an escape flue 27 which may be closed by a damper 28. One of the sides of the vault 23 shows a door 29 for engaging a ladle and removing the slag from the top of the bath. 80

The opposite side of the vault is provided with a duct 30 for introducing the metal. This duct is slightly sloping and its lower part is provided with rollers 31. It is closed by two doors 32, 33 hinged by their top 90 edge to the duct and closing under the effect of their weight whilst bearing in a slanting position against the said duct. A ledge 34 is disposed for receiving the metal before its introduction into the hearth. A grid 35 divides the two parts 36, 37 of the bath corresponding to the vault 23 and the cover 24. The stirring device, not shown, and a molten metal removing device 37' are disposed in part 37. 95

The vault 23 and the whole of the hearth are carefully heat-insulated.

The hearth works in the following manner:

When the burner 22 is ignited, the hot 105 flames and gases pass through the flue 19, the flues 20 and 21 whilst heating the whole mass of solid metal disposed in the crucible 15 which melts easily at 240° without any danger of breaking the crucible. The gases 110

pass through the pipes 25, 26 into the vault 23 and escape through the chimney 27. The gases in the vault 23 are at a temperature of about 500° C. The optimum temperature for the bath is 300 to 350° C. As soon as the bath is molten, the stirring device (not shown) is actuated and when the metal has reached the desired temperature the metal is removed into the molds. The addition of 5 fresh metal ingots or of plates is provided by disposing them on the ledge 34 and pushing them against the door 33 which rises and lets them pass. They move forwards over the rollers 31 up to the door 32 which they 10 also raise before falling into the bath.

As stated hereinabove, it is of advantage to throw the old plates into the bath without cleaning them as usual heretofore. Under the influence of the temperature of 500° 15 under the vault 23, the oils and the rosin due to the inking of the said plates burn on the surface of the bath under the vault and their reducing action together with that of the gases from the hearth diminishes the amount 20 of slag forming on the surface of the bath.

Due to the small deperdition of heat in a furnace built in the above described manner, the molten bath may be kept a long time without becoming solid. It is therefore of 30 advantage to allow the oil burner 22 to burn at full rate, the damper 28 being closed when the operation of the burner is stopped.

In a 9-ton hearth of the above type the economy in fuel over the old types is more 35 than 60%. The time necessary for the melting of a solid mass filling the crucible is only two hours and the production of slag is reduced by 25%. The results are even better when the burner instead of being disposed at the lower part of the arrangement 40 is disposed above the bath level whereby the flow of the gases is reversed as shown in dotted lines on Figs. 4, 5 and 6 where similar parts are shown by similar reference numbers. In this modification the burner 22 is 45 disposed at the end of the crucible and above the molten metal level. The flames and gases are led therefrom into the hearth through the duct 22' and after passing over the bath 50 return through 25 and 26 to the superposed flues through which they pass in the reverse direction to that shown on Figs. 1 to 3. Of course the exhaust flue 27 communicates on one hand with the end of the lower flues and 55 ends on the other with the stock 27' disposed next to the metal feed device. Thus the vault over the crucible may be entirely closed.

An advantage of this arrangement resides in that the impurities burn under the vault and 60 cannot be carried out through the exhaust flue whereby all danger of fire is avoided.

Moreover the fuel combustion is much reduced as the gases flow in a methodical direction which is opposite to that of the precedent case and the amount of slags produced is much reduced.

What I claim is:

1. A hearth for stereotype plate founding and the like comprising a crucible adapted to receive the plates and metal to be melted, 70 a burner, means for directing the flames and gases produced by the burner round and over the crucible, a vertical grid dividing the crucible in two parts, a vault over one part thereof, means for feeding the plates and metal into the part covered by the vault, a flat cover over the other part of the crucible and means for removing the molten metal from the part of the crucible covered by the flat cover.

2. A hearth as claimed in claim 1 comprising a series of horizontal flues where-through the flames and gases are adapted to pass in succession round and below the crucible.

3. A hearth for stereotype plate founding and the like comprising a crucible adapted to receive the plates and metal to be melted, 90 a burner, means for directing the flames and gases produced by the burner round and over the crucible, a vertical grid dividing the crucible in two parts, a vault over one part thereof, a sloping channel for feeding the metal and plates into the part of the crucible covered by the vault, doors at each end of the channel adapted to be opened by the metal and plates passing into the crucible, a flat cover over the other part of the crucible and means for removing the molten metal from the part of the crucible covered by the flat cover.

4. A hearth for stereotype plate founding and the like comprising a crucible adapted to receive the plates and metal to be melted, 95 a burner, a conduit connecting the burner with the crucible above the metal level, ducts connected with the upper part of the crucible, a series of successive horizontal flues the first of which are connected with the said duct, a chimney connected with the last flue, a vertical grid dividing the crucible in two parts, a vault over one part thereof, means for feeding the plates and metal into the part of the crucible covered by the vault, a flat cover over the other part of the crucible, and means for removing the molten metal from the part of the crucible covered by the flat cover.

In testimony whereof I have affixed my signature,

JEAN RABATÉ.
